UNITED STATES PATENT OFFICE.

IGNATZ HOFFMANN, OF FORD CITY, PENNSYLVANIA.

MACHINE FOR THE MANUFACTURE OF PAPER EXCELSIOR.

1,312,986.

Specification of Letters Patent.

Patented Aug. 12, 1919.

Application filed March 8, 1919. Serial No. 281,411.

To all whom it may concern:

Be it known that I, IGNATZ HOFFMANN, a citizen of the United States, residing at Ford City, in the county of Armstrong and State of Pennsylvania, have invented certain new and useful Improvements in Machines for the Manufacture of Paper Excelsior, of which the following is a specification, reference being had to the accompanying drawings.

This invention relates to an improved machine for the manufacture of paper excelsior.

It is the aim of the present invention to provide a machine, whereby waste-paper of all kinds may be manufactured or converted into excelsior, which is especially adapted for packing purposes, that is to say, for packing fancy glass, porcelain, enamel and china ware, and also for packing gold and silver articles, and electric and glass globes and numerous other fragile or frangible articles.

However, the waste-paper that is designed to be converted into excelsior should be entirely free of wood splinters, or any hard substance such as metal or the like, the object being to avoid dulling or injuring the cutting elements in the machine.

A further object of the invention is the provision of a machine of this kind, which is simple in construction, efficient and effective in operation, and may be installed in operation at a particularly low cost.

The invention further aims to provide an improved housing, for housing the operating parts of the machine, namely a plurality of cutting elements, such as knives, and furthermore, it is the aim to construct this housing so that it is entirely air-tight, whereby the waste-paper will have a free passage through the mechanism, so as to be effectively operated upon, in order to convert the same into excelsior of a character suitable for packing purposes.

The invention further aims to provide improved means for reciprocating the several cutting elements.

The invention further aims to provide air blasting means below the cutting elements for ejecting a blast of air in various directions by means of alternate perforations in the pipe of the air blasting means, for the purpose of forcing the paper into the spaces between the cutting elements, whereby the

paper may be cut and reduced in thin strips of a character suitable for packing purposes.

A further object of the invention is to provide means for keeping the waste-paper in the spaces between the knives, and also to provide means carried by the housing outwardly through which the paper converted into excelsior may be discharged. The reciprocating knives reduce the paper into strips, and the paper thus cut into strips may be used as packing excelsior.

A further object of the invention is to provide means adjacent the cutting elements or knives to insure an equal distribution of the air and the paper.

While the structure of the machine at present disclosed is deemed preferable, it is obvious that the machine when reduced to a practical form for commercial purposes is susceptible to alterations, and the right to these alterations is claimed, provided they are comprehended within the scope of what is claimed.

The invention comprises further features and combination of parts, as hereinafter set forth, shown in the drawings, and claimed.

In the drawings:

Figure 1 is a view of the machine constructed in accordance with the invention, showing the parts of the housing broken away, and parts of the mechanism in elevation, and illustrating the reciprocating cutting elements.

Fig. 2 is a vertical sectional view through the same on line 2—2 of Fig. 1.

Fig. 3 is a horizontal sectional view on line 3—3 of Fig. 1.

Fig. 4 is an enlarged detail view of several of the plurality of cutting elements, and the guides, and the reciprocating means.

Fig. 5 is a sectional view on line 5—5 of Fig. 4.

Figs. 6 and 7 are detail views of portions of one of the knives or paper stripping elements.

Referring to the drawings 1 designates a housing which may be in convenient shape or configuration, preferably such as that now illustrated. The lower part of the housing is provided with a compartment, in which a conventional form of motor 2 is located, and also a blow fan 3, the fan member of which is driven by the motor. The driving shaft 4 of the motor is provided with a driving pulley 5, which is engaged by a suitable driving belt 6.

Above the compartment 7 the housing has a vertically arranged channel or chamber 8.

This chamber or channel extends substantially the full width of the housing, and vertically from a point adjacent the compartment. Adjacent the roof of the housing, say for instance, a short distance below conveniently arranged excelsior discharging passages 9, which are oppositely arranged, are provided. However, this chamber or channel is restricted from the front to the rear, and rising from the bottom of the chamber are oppositely arranged supports 10. These supports converge toward each other and are connected in any suitable manner to the super-imposed plates 11. These plates are spaced, such space being employed for the reception of the vertically reciprocating cutting elements or knives 12. Below the plates 11 are additional plates 13, which are also spaced, in a manner similar to the plates 11, said space designed for the purpose of the reception of the lower ends of the cutting elements or knives. The upper and lower end portions of the knives are provided with elongated slots 14 and 15 through which the upper and lower series of bolts 16 and 17 pass. By virtue of the bolts and the slots the cutting elements or knives are suitably guided in their reciprocating motions, thereby preventing relative displacement. The bolts above and below are arranged in such spaced relation, in horizontal direction, as to guide the knives or cutting elements, in order to arrange them with their cutting edges spaced. The spaces between the cutting edges of the cutting elements or knives are provided for the reception of the waste-paper or the like, which is distributed and forced therein by blasts of air or other suitable means, in order to be reduced to a stripped condition. The stripped condition of the paper should be of such a character, that the paper may be used as excelsior, for packing purposes. The upper ends of the cutting elements or knives (the adjacent spaced cutting edges of which have adjoining beveled parts) are provided with reduced extensions 18, to which links 19 are connected. These links are in turn pivotally connected to the various cranks 20 of the crank shaft. These cranks extend radially and in staggered directions radially from the axis of the shaft, whereby vertical reciprocating motions may be imparted to the cutting elements or knives. This crank shaft is mounted in bearings of the housing, and one end thereof is provided with a pulley 21, which is engaged by the driving belt 6. It is obvious that when the motor is driven, revoluble movements are imparted to the crank shaft, which in turn impart movements to the reciprocating cutting elements or knives.

Arranged adjacent the lower ends of the cutting element or knives, is a pipe or flue 22, which has a pipe or flue of communica-

tion with the blow fan 3, and by means of the blow fan a blast of air is forced through the pipe, whereby the air may escape through the perforations 23 of the flue or pipe 22. It is to be noted that these perforations 70 23 are arranged in staggered relations with one another. Also it is to be observed that the pipe or flue 22 is so arranged below and offset from the lower ends of the cutting elements or knives and since the perforations 75 23 (which are elongated) are in staggered relations, the air discharged from the perforations will pass upwardly through the space between the knives or cutting elements, and the front wall of the housing, whereby 80 feeding the paper through the chamber, and equally distributing the paper and the air, whereby the paper may be effectively stripped, to be used as excelsior.

Further, in order to insure proper distribution of the air and paper, a plate or deflector 25 is arranged at the rear of the cutting elements or knives and adjacent thereto. This plate or deflector not only insures a proper distribution of the air and paper, 90 but also maintains the paper in its proper relative position with relation to the knives in order that it may be cut.

As shown clearly in the drawings, more especially Fig. 1, the upper part of the 95 housing is provided with a conical wall 26. In other words, a wall or ceiling which inclines downwardly from opposite sides of the housing, the inclined surfaces 27 of which act to deflect the excelsior paper toward and through the discharge passages 9, obviously since the blast of air is projected and distributed upwardly. The upwardly traveling air, which distributes the paper excelsior as well as feeding the same upwardly is also deflected toward the discharge 100 passages, so that when escaping, the paper excelsior will also be discharged. The paper excelsior when discharged may fall in suitable receptacles, not shown, and may 105 then be put up in bundles or packages, such as is suitable to be sold to the trade for packing purposes.

The housing is provided with an opening 30, through which the waste-paper may be 110 passed, said opening having a hinged closure 31.

In operation the waste-paper is passed through the opening 30 into the chamber 8. The blast of air emanating from the 115 perforations 23 of the pipe or flue 22 forces the waste-paper upwardly through the chamber or passage 8, and in between the severing members or knives 12, which, as heretofore stated are constantly reciprocated. It is to be noted that the knives have their cutting edges 12^a facing in a direction toward the forward part of the chamber or passage 8. Obviously as the paper is blown or fed toward the cutting 120 125 130

edges 12^a (the knives being constantly reciprocated,) the paper may be cut into strips. The air blast constantly blowing through the chamber or passage 8, feeds the paper between the knives, and into the upper part of the chamber. It is to be further noted that an additional flue or pipe 22^a is arranged in the chamber 8^a (which is in the rear of the chamber 8,) and extending upwardly from the flue 22^a is a plurality of vertical flues 22^b. The upper ends of the flues 22^b pass through the wall 22^c. By this arrangement and construction, it will be seen that there is a plurality of air blasts projected into the upper part of the chamber or passage 8, acting to draw or suck the paper through the passage or chamber and in between the knives, and subsequently blow the paper excelsior out through the discharge passages 9. This sucking or drawing action occurs since the upper ends of the vertical flues 22^b terminate at points substantially where the intermediate portion of the chamber or passage 8 merges into the upper portion thereof. It is to be observed that the flue 22^a is also connected to and in communication with the blow fan 3, as shown at 22^d.

The invention having been set forth, what is claimed as new and useful is:

1. In a machine for the manufacture of paper excelsior, the combination with a housing provided with a compartment and super-imposed chamber, of vertically reciprocating spaced paper severing elements, mounted in the chamber, actuating means for the elements, and means below the elements for equally distributing air and the paper to be severed through the chamber and in the chamber between the knives.

2. In a machine for the manufacture of paper excelsior, the combination with a plurality of reciprocating equally spaced severing elements, actuating means therefor, a chamber in which the elements are located, and through which the paper to be severed travels, means for forcing a blast of air through the chamber for feeding the paper, and means for distributing air the full area of the chamber, whereby the paper is likewise distributed.

3. In a machine for the manufacture of paper excelsior, the combination with a plurality of reciprocating equally spaced severing elements, actuating means therefor, a chamber in which the elements are located, and through which the paper to be severed travels, means for forcing a blast of air through the chamber for feeding the paper, and means for distributing air the full area of the chamber, whereby the paper is likewise distributed, said air and paper distributing means comprising a flue in communication with the air blasting means arranged below and offset from the lower

ends of the elements and having means in staggered relations to insure a distribution of the air and paper.

4. In a machine for the manufacture of paper excelsior, the combination with a plurality of reciprocating equally spaced severing elements, actuating means therefor, a chamber in which the elements are located, and through which the paper to be severed travels, means for forcing a blast of air through the chamber for feeding the paper, and means for distributing air the full area of the chamber, whereby the paper is likewise distributed, and deflecting means at the rear of the elements to additionally aid in distributing the air and paper and keeping the same in the spaces between the elements.

5. In a machine for the manufacture of paper excelsior, the combination with a plurality of reciprocating equally spaced severing elements, actuating means therefor, a chamber in which the elements are located, and through which the paper to be severed travels, means for forcing a blast of air through the chamber for feeding the paper, and means for distributing air the full area of the chamber, whereby the paper is likewise distributed, said air and paper distributing means comprising a flue in communication with the air blasting means arranged below and offset from the lower ends of the elements and having means in staggered relations to insure a distribution of the air and paper, and deflecting means at the rear of the elements to additionally aid in distributing air and paper and keeping the same in the spaces between the elements.

6. In a machine for the manufacture of paper excelsior, the combination with a plurality of reciprocating severing elements equally spaced with their severing edges in parallelism, of actuating means for the elements, a housing having a chamber for the elements, through which chamber the paper to be severed passes, means for feeding the paper through the chamber, and deflecting means on one side of the severing elements, whereby the paper may be equally distributed in its passage through the chamber.

7. In a machine for the manufacture of paper excelsior, the combination with a plurality of reciprocating severing elements operable in parallelism and having their severing edges equally spaced, of means for actuating the elements, a chamber for the elements and provided with outlet flues through which the excelsior may be discharged, and means for deflecting excelsior through the outlet passages.

8. In a machine for the manufacture of paper excelsior, the combination with paper severing means, of actuating means therefor, a chamber for the severing means, means for feeding the paper through the chamber, and means below and offset from the lower

- part of the severing means for equally distributing the feeding means and the paper through the chamber in contact with and past the severing means.
5. In a machine for the manufacture of paper excelsior, the combination with paper severing means, of actuating means therefor, a chamber for the severing means, means for feeding the paper through the chamber, and means below and offset from the lower part of the severing means for equally distributing the feeding means and the paper through the chamber in contact with and past the severing means, said chamber having outlet 10 70 75 passages, and means for deflecting the feeding means and the paper into and through said passages.
10. In a machine for the manufacture of paper excelsior, the combination with a housing provided with a chamber, of paper severing means mounted in the chamber, actuating means therefor, an air blasting means below the chamber, a flue below and offset from the lower part of the severing 20 25 30 means and in communicative connection with the air blasting means and provided with means for equally distributing the air and the paper through the chamber and in coöperation with the severing means, and a deflecting means to one side of the severing means.
11. In a machine for the manufacture of paper excelsior, the combination with a housing provided with a chamber, of paper severing means therein, air blasting means below the chamber, a flue below and offset from the lower part of the severing means and in communicative connection with the air blasting means, and provided with perforations in staggered relations, for equally distributing the air and the paper through the chamber and in coöperation with the severing means.
12. In a machine for the manufacture of paper excelsior, the combination with paper severing means, of actuating means therefor, a chamber for the severing means, means for feeding the paper through the chamber, and means below and offset from the lower part of the severing means for equally distributing the feeding means and the paper through the chamber, said chamber having outlet 45 50 55 60 65 passages, and means for deflecting the feeding means and the paper into and through said passages, and deflecting means to one side of the severing means to additionally distribute the feeding means and the paper.
13. In a machine for the manufacture of paper excelsior, the combination with a housing provided with a chamber, of paper severing means mounted in the chamber, actuating means therefor, and air blasting means below the chamber, a flue below and offset from the lower part of the severing 60 65 means and in communicative connection 70 75 80 85 90 95 100 105 110 115 120 125 130
- with the air blasting means and provided with means for equally distributing the air and the paper through the chamber and in coöperation with the severing means, and a deflecting means to one side of the severing means, discharging passages in opposite walls of the chamber adjacent its top thereof for the severed paper, and means at the top of the chamber for deflecting the air and the severed paper through the discharging passages.
14. In a machine for the manufacture of paper excelsior, the combination with a housing provided with a chamber, of paper severing means mounted in the chamber, actuating means therefor, an air blasting means below the chamber, a flue below and offset from the lower part of the severing means and in communicative connection with the air blasting means and provided with means for equally distributing the air and the paper through the chamber and in coöperation with the severing means, and a deflecting means to one side of the severing means, said severing means comprising a plurality of vertically reciprocating cutting elements, and means for guiding said elements.
15. In a machine for the manufacture of paper excelsior, the combination with a housing having a chamber, of vertically reciprocating paper severing elements mounted in said chamber, upper and lower spaced plates between which the elements reciprocate, said plates having slot and pin connections with the elements for guiding the same, means for feeding the paper through the chamber in coöperation with the severing elements, and means below and offset from the lower part of the severing elements and in communicative connection with the feeding means for equally distributing the feeding means and the paper through the chamber and in coöperation with the severing elements.
16. In a machine for the manufacture of paper excelsior, the combination with paper severing means, of actuating means therefor, a chamber for the severing means, and pneumatic means for feeding the paper through the chamber and equally distributing the paper in contact with the severing means.
17. In a machine for the manufacture of paper excelsior, the combination with paper severing means, of actuating means therefor, a chamber for the severing means, pneumatic means for feeding the paper through the chamber, and means below and offset from the lower part of the severing means for directing the pneumatic means through said chamber, whereby the paper is equally distributed toward, in contact and past the severing means.
18. In a machine for the manufacture of paper excelsior, the combination with recip-

rocating paper severing means, of actuating means therefor, a chamber having guides for the severing means, means for feeding the paper through the chamber, and means 5 below and offset from the lower part of the severing means for directing the feeding means, whereby the paper may be equally distributed toward, in contact and past the severing means.

10 19. In a machine for the manufacture of paper excelsior, the combination with paper severing means, of actuating means therefor, a chamber for the severing means, means for feeding the paper through the chamber, 15 and means below and offset from the lower part of the severing means for directing the feeding means, whereby the paper may be

equally distributed toward, in contact with and past the severing means.

20. In a machine for the manufacture of 20 paper excelsior, the combination of a plurality of reciprocating severing elements, of actuating means therefor, a chamber having guides for said elements, and pneumatic means for feeding the paper through the 25 chamber, directing and equally distributing the paper in contact with the severing element.

In testimony whereof I hereunto affix my signature in the presence of two witnesses. 30
